(57) **CLAIM**

The ornamental design for a character display panel, as shown and described.

DESCRIPTION

FIG. 1 is a perspective view of a character display panel showing the claimed design;

FIG. 2 is a front elevational view thereof;

FIG. 3 is a left side elevational view thereof; the right side elevational view being a mirror image of FIG. 3;

FIG. 4 is a top plan view thereof; the bottom plan view being a mirror image of FIG. 4; and,

FIG. 5 is a perspective view of a character display panel including a plurality of display units in another embodiment showing the claimed design.

The broken lines are directed to environmental features and are for illustrative purpose only; the broken lines form no part of the claimed design.

1 Claim, 4 Drawing Sheets
